UNITED STATES PATENT OFFICE.

CHRISTIAAN VISSER, OF NEW YORK, N. Y.

DAVIT.

1,196,316.

Specification of Letters Patent. Patented Aug. 29, 1916.

Application filed December 14, 1915. Serial No. 66,850.

To all whom it may concern:

Be it known that I, CHRISTIAAN VISSER, a subject of the Queen of the Netherlands, residing at New York, in the county and 5 State of New York, have invented certain new and useful Improvements in Davits, of which the following is a full, clear, and exact specification.

This invention relates to davits for supporting and lowering life-boats from the decks of larger vessels, and it has for its object to provide mechanical means for turning the davits for swinging the life-boats over the side of the ship, in order that this 10 operation may be positively accomplished in spite of the listing of the ship as often occurs after a collision or injury to the hull of the ship. When the davits have to be swung out by hand, the listing of the ship 15 one way makes it practically impossible to launch the life-boats from the upper side of the deck, and many lives have been lost on this account. It is the aim of the present invention to provide means which will make 20 it possible to launch the life-boats from the upper side of the deck at such times and thus render the full quota of life-boats useful in such cases of emergency.

Other objects will appear as the description proceeds.

The invention will be first hereinafter described in connection with the accompanying drawings, which constitute a part of this specification, and then more specifically defined in the claims at the end of the description.

In the accompanying drawings, wherein similar reference characters are used to designate corresponding parts throughout the 40 several views:—Figure 1 is a broken elevation of the middle portion of a davit, constructed substantially in accordance with this invention and showing the mechanical means for turning the same for swinging 45 the life-boat over the side of the ship. Fig. 2 is a sectional view on the line II—II of Fig. 1, and Fig. 3 is a diagrammatic plan view of a pair of davits, showing the arrangement of the operating cranks and 50 how said davits are swung out one at a time for launching a life-boat.

In Fig. 1, 1 designates the boat deck of the ship, and 2 and 3 are plates secured above and below the same, respectively, by 55 bolts 4 for journaling the middle portion

of the davit 6. The upper plate 2 is preferably provided with an upwardly extending sleeve 5 to give a better bearing for the davit. As illustrated, the base of the davit extends down through the boat deck and 60 lower plate 3 to the main deck (not shown). To prevent axial movement of the davit, it is provided with a circumferential groove 8 a short distance below the bottom plate 3, and a collar 7, having screws or bolts 9 65 extending into said groove, is placed around the middle portion of the davit and in contact with the under face of said plate 3.

Spaced some distance above the deck, a plate 10 is supported rigidly from the plate 2 by rods 11, preferably two in number, one on either side of the davit, as shown in Fig. 2. The lower ends of said rods are provided with shoulders 12 to rest upon the top surface of the plate 2, and with screw threaded 70 extremities 13 to engage sockets in said plate. The upper ends of the rods 11 are also shouldered at 14 and have their extremities passed through the plate 10 and screw threaded, as at 15, to receive binding 75 nuts 16.

Between the plates 2 and 10 the davit is screw threaded, as at 17, and around said screw threaded portion is fitted a collar 18 80 having an internally screw threaded passage 85 to fit the threads 17, and other passages 19 through which the rods 11 extend as a means for guiding said collar 18. An internally screw threaded bushing 20 is carried by the collar 18 and through it runs a screw shaft 90 21 journaled at 22 in the plate 2, and at 23 in a bushing 24 in the plate 10. A beveled pinion 25 is keyed to the shaft 21 and meshes with a pinion 26 on a shaft 27 which is journaled in a downwardly bent portion 28 of 95 the plate 10. The shaft 27 is fitted with a crank 29 having an operating handle 30.

From the foregoing it will be seen that when the crank 29 is turned in one direction, the collar 18 will be moved upwardly, while the reverse turning of said crank will lower the collar 18, and that the movement of said collar will cause the davit to turn by reason of the threads 17. In Fig. 3, the davit 6 is shown as it is used with a second davit 60 which is constructed exactly like the davit 6 except that the thread thereon is inclined in the reverse direction from the thread 17 on the davit 6, in order to make the davits 105 turn toward each other, as indicated in the 110

dotted lines 31 of Fig. 3. When a life-boat 32 is to be swung out from the deck for launching, one davit is operated at a time, so as to move one end of the boat outward first, as indicated by the dotted line 33 in Fig. 3, after which the other davit is operated to swing out the other end of the boat. It will be noted that the operating cranks 29 are arranged out of the way and do not interfere with the movement of the boat in launching the same.

Having thus described my invention, what I claim as new and desire to secure by Letters Patent of the United States is:

- 15 1. The combination with a davit having screw threads thereon, of a collar having a correspondingly threaded passage fitted around the threaded portion of the davit, means for moving said collar axially along the davit for turning the latter, and means for preventing said collar turning with the davit.
- 20 2. The combination with a davit having screw threads thereon, of a collar having a

correspondingly threaded passage fitted 25 around the threaded portion of the davit, said collar having another screw threaded passage therein, a screw shaft running through said latter passage, means for turning said shaft to move the collar axially 30 along the davit and thus cause the latter to turn, and means for preventing said collar from turning.

3. The combination with a davit having screw threads thereon, of a collar having a 35 correspondingly threaded passage fitted around the threaded portion of the davit, said collar having another screw threaded passage therein, a screw shaft running through said latter passage, a pinion keyed 40 on the shaft, an auxiliary shaft, a pinion on the auxiliary shaft meshing with the pinion on the screw shaft, and a crank for turning the auxiliary shaft.

In testimony whereof I have signed my 45 name to this specification.

CHRISTIAAN VISSER.
